Primary Examiner — David Muller(74) *Attorney, Agent, or Firm* — McKee, Voorhees & Sease, P.L.C.(57) **CLAIM**

We claim the ornamental design for a tip for vibrating anesthesia device, substantially as shown and described.

DESCRIPTION

FIG. 1 is a perspective view of the vibrating anesthesia device tip of the present invention.

FIG. 2 is a rear perspective view of the tip.

FIG. 3 is a left side elevation view of the tip.

FIG. 4 is a right side elevation view of the tip.

FIG. 5 is a rear elevation view of the tip.

FIG. 6 is a front elevation view of the tip.

FIG. 7 is a top plan view of the tip; and,

FIG. 8 is a bottom plan view of the tip.

The features shown in broken lines depict environmental structure only and form no part of the claimed design.
